Primary Examiner — Ramon R. Hoch*Assistant Examiner* — Karen S Acker(74) *Attorney, Agent, or Firm* — Kilyk & Bowersox, P.L.L.C.; Valerie Calloway(57) **CLAIM**

The ornamental design for a nonwoven fabric, as shown and described.

DESCRIPTION

FIG. 1 is an isometric view of a nonwoven fabric showing my new design;

FIG. 2 is a top plan view thereof;

FIG. 3 is an isometric view of a second embodiment of my new design;

FIG. 4 is a top plan view thereof;

FIG. 5 is an isometric view of a third embodiment of my new design; and,

FIG. 6 is a top plan view thereof.

The pattern of the nonwoven fabric repeats uniformly throughout the surface of the design. The nonwoven fabric is flat and planar. The rear side and the broken lines surrounding the nonwoven fabric form no part of the claimed design.
